GRAVITY ACTUATED MECHANICAL TOY

Richard Martin, Winter Park, Fla.

Application June 22, 1956, Serial No. 593,234

1-Claim. (Cl. 46—149)

This invention relates to amusement devices and particularly to amusement devices which may be classified as toys.

An object of the present invention is to provide an amusement device for both adults and children wherein the pull of gravity is used to provide the mode of force necessary to cause the toy to perform, the performance being a series of motions, movements and gyrations that follow a general pattern of oscillations and translations. More explicitly, the toy is so constructed that it is initially supported on an inclined plane surface by a center protrusion on the bottom, or base, of the toy and any point on the outer edge of a disk that rises from the bottom, or base, and when set in motion as by tapping gently or relying on the vertical component of the gravitational force available on an inclined plane surface, it tips slightly so that it rolls on the circular rim defined by the edge of the bottom of the toy and the edge of the previously mentioned disk, with the center protrusion preferably separated from the inclined surface, even if only an extremely small fraction of an inch at some part of the oscillatory movement of the toy. When the toy reaches the top of its swing the center of gravity of the toy is approximately vertically over the center protrusion and therefore the toy commences to settle down, momentarily resting on the edge of the disk, this resting point being the sole support of the toy. Because of the high rotary inertia of the toy it continues revolving about this point of support so that the center of the toy swings slightly forward as it continues to settle downwardly on the inclined plane surface. The toy is now supported on the center protrusion and the edge of the disk and is ready to oscillate in the opposite direction. Accordingly, the toy has moved a short distance down the inclined plane and due to inertia of the toy is ready to begin an oscillation on the inclined plane surface in the opposite direction from the first described operation.

A further object of the present invention is to provide a toy that has been made in accordance with the above, wherein the disk that constitutes a part of the bottom of the toy is eccentric with respect to the longitudinal axis of the body and the protrusion that rises from the surface of the disk. In this way the toy is caused to face generally in one direction, whereby if the toy is made as a caricature of an animal or a human being or any other object which has normally a front and a rear, the direction of motion down the inclined plane is automatically such as to have the toy facing in the front direction.

Another object of the present invention is to provide a toy capable of providing amusement for children and adults, the toy being manufacturable at an extremely low cost and being susceptible to assuming many forms and configurations so that a large variety of different appearing toys may be presented, each embodying the same principles of operation.

These together with other objects and advantages which will become subsequently apparent reside in the details of

2

construction and operation as more fully hereinafter described and claimed, reference being had to the accompanying drawings forming a part hereof, wherein like numerals refer to like parts throughout, and in which:

Figure 1 is a perspective view of a toy which has been constructed in accordance with the principles of the invention, this toy being shown in its operative condition that is, mounted on an inclined plane surface and showing in phantom lines two extremes in the oscillatory movement of the toy;

Figure 2 is a longitudinal sectional view of the toy of Figure 1;

Figure 3 is a bottom view of the toy in Figure 2;

15 Figure 4 is a fragmentary sectional view showing the toy in its initial or starting position, resting on the protrusion and a part of the edge of the disk on the bottom of the toy;

Figure 5 is a fragmentary sectional view showing another stage in one oscillation of the toy, this other stage being after the toy has been set in motion, this view illustrating principally that the toy oscillates on the rim of the bottom and the circular edge of the disk that constitutes a part of the bottom, and;

20 25 Figure 6 is a fragmentary sectional view showing the toy as it reaches the top of its oscillatory swing, the toy momentarily resting on the edge of the disk, this constituting the sole support for the toy at this instant.

In order to demonstrate the principles of the invention, there is an inclined plane surface 10 illustrated, this surface being in the form of a tilted table top, board or other improvised panel. By selection of a material or a covering for the material having a coefficient of friction amiable to the bottom of the toy, the panel on which 30 35 the toy is operative may be used to enhance the motions of the toy. For example, a toy constructed of brittle material, as a synthetic resin such as "Bakelite" together with a steel protrusion has been found to operate extremely satisfactorily on a plywood panel. Although the same toy will operate on a smoother surface or on a rougher or on a surface having a higher coefficient of friction, better results were obtained on the wood panel.

Toy 12 is constructed as a person, but it is to be understood that the toy may be constructed in simulation, 40 mock simulation or caricature of any animal, person or object. The specific illustration involves a body 14 that may be molded plastic, papier mache or other preferably lightweight materials. The body has a longitudinal axis on which the neck 16 and head 18 are located and 45 through which the center pin 20 passes. This center pin may be of metal, wood or other materials and terminates in a protrusion or point 30, after passing through the bottom, or base, 32 of the toy. The bottom may be formed integral with the remainder of the body as a separate part and cemented or otherwise joined thereto. This is an important part of the toy 12 and consists of 50 a circular member having a circular rim 40 and the protrusion 30 in its axis and a bottom surface 41 from which circular disk 42 protrudes. The disk is of a thickness greater than the length of protrusion 30, but only slightly so. The circular edge 50 of disk 42 constitutes a line contact seat for the toy during its normal operation. The bottom of the toy is made rather heavy with 55 respect to the remainder of the toy, and the toy is so constructed that the center of gravity of it is rather high. In this way the rotary inertia of the toy as it is in operation remains sufficiently high to keep the toy in continuous oscillatory and transitory motion.

In operation, the toy is placed at rest on the inclined plane surface and is supported by the center projection 30, as a point, and on the edge 50 of the inner circle which is defined by the edge of disk 42. This condition

is shown in Figure 4 and at this instant the rim 40 is completely separated from the supporting surface. By having the disk 42 eccentric of the body of the toy (Figure 3) the normal rest position will be with the front of the toy facing downwardly of the supporting surface (see Figure 1) and the toy will maintain in general this attitude during the motions thereof.

The toy may be set in motion in two ways. It may be tapped gently forcing it to swing in one direction or it may be set in motion automatically by the vertical component of the gravitational pull, as by tilting the supporting surface 10 slightly in excess of the inclination required to keep the toy in operation once it commences oscillating. In either case the toy tips slightly forward and rolls on edge 50 and rim 40 simultaneously. This condition is portrayed in Figure 5, this figure showing clearly that the protrusion 30 is preferably separated from the supporting surface 10. As the toy rolls, for example to the left as shown in Figure 1, it rolls on the rim 40 and edge 50 until it reaches the top of its oscillatory swing at which position the center protrusion begins to settle down, the toy momentarily or instantaneously resting on the edge 50 alone.

However, due to the high rotary inertia the toy continues revolving about this point on edge 50 so that the center of the toy, for example as defined by protrusion 30, swings slightly forward as it settles onto surface 10 in order to reach the starting position (Figure 4) again. However, this starting position is at the top of an oscillatory swing of the toy and there is available in the toy enough potential energy to swing the toy again in a second stage of operation, this second stage being a second oscillatory swing in the opposite direction. Accordingly, in its gyrations, the toy swings in a direction generally transverse to the inclination of surface 10 and at the same time rotates slightly. At the top of the swing the toy rotates additionally and progresses forwardly that is downwardly of surface 10 a slight distance. Thereafter the

toy commences to swing in the opposite direction following the same procedure as previously described.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

In combination, a downwardly inclined panel and a gyrating toy thereon having an upright elongated body, and means on said body engageable with said panel and adapting said body to oscillate on the panel between limits of oscillatory movement under pull of gravity and to rotate about its longitudinal axis in response to such oscillation, said means comprising a circular flat bottom on said body having a circular bottom edge concentric to said axis, a protuberance depending from said bottom in said axis, and a flat disk fixed on and depending from said bottom eccentrically of the same and having a bottom edge below said circular edge eccentric to said protuberance and spaced inwardly of said circular edge and on which and said circular edge said body is oscillatable between said limits and tiltable in opposite directions on said eccentric edge and rotatable in said limits to lower and lift said protuberance onto and off said panel, respectively, and revolve the protuberance downwardly of the panel for oscillation of said body on said eccentric edge and the lowered protuberance in said limits and gravitational rotation of said body downwardly of the panel on said eccentric edge when the protuberance is raised.
